UNITED STATES PATENT OFFICE.

JOHN HENRY FLATLEY, OF LITTLE YORK, ILLINOIS.

ROAD-GRADING MACHINE.

Application filed January 31, 1920. Serial No. 355,517.

To all whom it may concern:

Be it known that I, JOHN HENRY FLATLEY, a citizen of the United States, a resident of Little York, in the county of Warren and State of Illinois, have invented new and useful Improvements in Road-Grading Machines, of which the following is a specification.

This invention has reference to road grading machines, and it has for its principal object, to provide in such a machine, a pair of revoluble road grading members.

The invention has for a further object, to construct a road grading machine with revoluble grading members, each formed with a plurality of radially arranged road engaging blades or vanes, and in the provision of a traction-wheel geared to said revoluble members for rotating the same as the grader is drawn over the road to be graded.

The invention has for a still further object, to construct a grader with rotatable grading blades or vanes, and to provide a traction member geared to said blades in a manner to impart a comparatively slow rotative movement to said blades or vanes, as the grader is drawn over the road to be graded.

The invention has for a still further object, to construct a grader with a pair of rotatable members provided with a plurality of radially arranged road engaging blades; a traction wheel geared to said members being employed to transmit rotary movement to the members as the grader is drawn over the ground; the supporting frame and operating parts for the members being of a flexible character to permit the grader to accommodate itself to the irregularities of the road, and yet do efficient work; levelers being provided to trail the revoluble members so as to smooth and level any uneven or rough places.

That the invention may be more fully understood, reference is had to the accompanying drawings forming part of the present description, in which—

Fig. 1 is a plan view of my improved grading machine;

Fig. 2 is an elevation partly in section, as the same would appear if taken on the line 2—2 Fig. 1, looking in the direction of the arrow, and

Fig. 3 is an elevation partly in section,

as the same would appear if taken on the line 3—3 Fig. 1, looking in the direction of the arrow.

Like characters of reference denote corresponding parts throughout the figures.

My road grader differs from those heretofore suggested and used, in that I employ revoluble members having road engaging blades or vanes, instead of employing a fixed scraping blade, even though such a blade is adjustably supported, whereby its angularity may be changed relatively to the road. The result with the use of my machine is to effectually scrape all ridges and fill all furrows, such as those made by vehicle and automobile wheels, which is a result not obtainable through the use of the usual grading machine blade, which operates to leave the furrows only partly filled and the ridges not entirely smoothed.

In the preferred embodiment of the invention, I provide a pair of revoluble members 1, counter-parts of each other; i. e., including outer annular rings 2 connected to a centrally located socketed hub 3 by means of a plurality of radially arranged scraping or grading blades or vanes 4, and secured to the upper faces of said blades or vanes are large gear wheels 5. The upper face of each blade or vane 4 between the outer rim of the gear wheel 5 and the ring 2 are dished out, as at 6 to clear worm-like wheels 7 which mesh with the gear wheels 5. It will be seen that the speed of rotation of the members 1 depend on the ratio between the wheels 5 and the worms 7, and that in this instance the members 1 are intended to rotate comparatively slow. It is also to be observed that the members 1 may be rotated in opposite directions to each, outwardly or inwardly, or in corresponding directions, through and by means of the construction of the threads on the worm wheels 7.

The frame of the grader preferably comprises the parallel beams 8 to which are secured and from which depend brackets 9, located axially of the members 1 and on their lower ends provided with spherical members or balls 10 held in the sockets of the hubs 3, forming a ball and socket connection for the members 1 about which they rotate, and to permit certain freedom of action of the members 1 as they travel on uneven roads. Connected to and extending forwardly from said beams 8 are yoke ex-

tensions 11 through which coupling is made with a tongue 12, and to which are connected and from which depend hangers or brackets 13 carrying rollers 14 on their lower ends which contact with the lower faces of the rings 1, the latter rolling on the former. Connected to and extending cross-wise of the tongue 12, is a beam 15, and said beam is braced from the tongue by 5 braces 16 and coupled to the yoke extensions 11 through coupling rods 17 and 18. The beams 8 are connected back of the centers of the rotary members 1 by the foot-board 19. Coupled to the rear ends of the beams 10 8 are rods 20 to which are pivotally connected the levelers or covering boards 21, which preferably overlap at their inner meeting ends, and connected by the short chains 22. To retain the boards 21 in a 15 substantially vertical position, as seen in Figs. 1 and 2, I provide the rods 20 near their rear ends with the rearwardly inclined lugs or projections 23 with which the upper half portion of the boards will bear as the 20 grader is drawn forward and thus hold the boards in the working positions illustrated.

Rollers 14^a similar to the rollers 14 are journaled on the lower ends of brackets 14^b depending from the rear ends of the beams 30 8, and bear against the upper surfaces of the rings 2. These rollers 14 and 14^a tend to hold the members 1 to their work while permitting a certain amount of freedom during rotation to permit them to accommodate themselves to the surface of the 35 ground.

I provide for the operation of the rotary members 1 from a traction member of the grader, as the grader is drawn over the road and the traction member is revolved. Such a traction member is designated 24, being a wheel of suitable size, from the periphery of which projects the spaced spikes or prongs 25 which enter the ground and thereby compel forced rotation of said wheel and the members 1 geared thereto. This traction wheel 24 is connected to a shaft or spindle 26 journaled in a yoke frame 27 extending rearwardly from the rear end of the tongue 12. To the opposite ends of the shaft 27 are connected universal couplings 28 to which short shafts 29 are connected, which are in turn coupled through universal couplings 30 with stub shafts 31 on 40 which are carried the worm wheels 7. These stub shafts are journaled in hangers 32 from the extensions 11 of the beams 8.

The tongue frame is comparatively rigid, but a flexible coupling is made between it 60 and the beams 8 in the connection of the rods 17 and 18, and by the use of the universal couplings 28 and 30, a flexible driving connection is made between the traction wheel 24 and the gear wheels 5, which gives 65 considerable latitude to the flexibility of

the grader and its operating parts, as will be understood, and essential to the effective operation of the same.

The tongue 12 is shown provided with a clevis 33 to adapt it to be connected to a 70 tractor or other vehicle to be drawn over the road.

Reference being had to Figures 2 and 3, it will be observed that the opposite ends of the blades or vanes 4 have rounded or beveled ends 34, which enables the same to be dragged over the road without catching into bridges, culverts or other obstructions, while being drawn forward.

I have elected to title the invention as a 80 road grading machine. At the same time I want it understood that as a grader, it also functions as a drag or surfacer.

While I have elected to show and describe the machine in one form and arrangement, it should be understood that it is capable of modification in construction and operation, and I therefore do not desire to be limited, except as defined by the appended claims.

What I claim is:

1. In a road grader, in combination, a pair of revoluble grading members, each having a plurality of radially arranged road engaging blades, and means to rotate said members as the grader is drawn over the 95 road.

2. In a road grader, in combination, a pair of revoluble grading members, a gear wheel associated with each member, a traction wheel which is rotated by contact with the ground, gearing connecting said traction wheel with said first mentioned gear wheels to rotate said members, said connecting gearing including universal couplings to provide flexibility in said operating connections. 100

3. In a road grader, in combination, a plurality of rotatably mounted radially arranged road engaging blades, and means to rotate said blades as the grader is drawn over the road. 105

4. In a road grader, in combination, a plurality of rotatably mounted radially arranged blades, a superimposed gear wheel connecting said blades, traction means for imparting rotation to said blades, and gearing connecting said traction means and gear wheel. 110

5. In a road grader, in combination, a pair of parallel arranged frames, an annular member rotatably connected to each frame, a plurality of radially arranged blades connected to each member, and means to rotate said members and blades as the grader is drawn over the road. 120

6. In a road grader, in combination, a pair of parallel arranged frames, an annular member rotatably connected to each frame, a plurality of radially arranged blades connected to each member, a gear wheel connected to each member, a traction wheel, 125 130

and gearing connecting said traction wheel with said gear wheels for rotating said members and blades.

7. In a road grader, in combination, a pair 5 of parallel arranged frames, an annular member rotatably connected to each frame, a plurality of radially arranged blades connected to each member, a draft frame extending forwardly of the revolving members, a traction wheel connected to said draft frame, a gear wheel connected to rotate with each member, and gearing connecting said traction wheel with said gear wheels.

8. In a road grader, in combination, a pair 15 of parallel arranged frames, an annular member rotatably connected to each frame, a plurality of radially arranged blades connected to each member, means to rotate said members and blades as the grader is 20 drawn over the road, and leveling boards connected to trail behind said revolving members.

9. In a road grader, in combination, a frame, a pair of annular rings, radially arranged blades connected to said rings, a 25 ball and socket coupling between the rings and said frame, rollers carried by the frame bearing above and below the said rings, and means to rotate the rings and blades as the grader is drawn over the road. 30

10. In a road grader, in combination, a frame, a pair of annular rings, radially arranged blades connected to said rings, a ball and socket coupling between the rings and said frame, rollers carried by the frame 35 bearing above and below the said rings, a gear wheel associated with each ring, a traction wheel, gearing connecting said traction wheel and gear wheels, and leveling boards connected to trail behind said blades. 40

In witness whereof, I have hereunto affixed my hand this 26th day of January, 1920.

JOHN HENRY FLATLEY.
